(57) **CLAIM**

The ornamental design for a battery charger for headset, as
shown and described.

DESCRIPTION

FIG. 1 is a left, front, and top perspective view of a battery
charger for headset;

FIG. 2 is a right, front, and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a left, front, and top perspective view thereof,
showing the state that the lid is opened;

FIG. 10 is a right, front, and top perspective view thereof,
showing the state that the lid is opened;

FIG. 11 is a front elevational view thereof, showing the state
that the lid is opened;

FIG. 12 is a rear elevational view thereof, showing the state
that the lid is opened;

FIG. 13 is a top plan view thereof, showing the state that the
lid is opened;

FIG. 14 is a bottom plan view thereof, showing the state that
the lid is opened;

FIG. 15 is a left side elevational view thereof, showing the
state that the lid is opened; and,

FIG. 16 is a right side elevational view thereof, showing the
state that the lid is opened.

The broken lines in the drawings are for the purpose of
illustrating portions of the battery charger for headset that
form no part of the claimed design.

1 Claim, 16 Drawing Sheets
